Inventor:

Benjamin F. Foss.

By

S. W. Bates

Atty.

UNITED STATES PATENT OFFICE.

BENJAMIN F. FOSS, OF PORTLAND, MAINE.

CHIMNEY STOP.

Application filed June 7, 1924. Serial No. 718,667.

To all whom it may concern:

Be it known that I, BENJAMIN F. Foss, a citizen of the United States, residing at Portland, in the county of Cumberland and State of Maine, have invented certain new and useful Improvements in Chimney Stops, of which the following is a specification.

My invention relates to safety devices to be used in buildings and it relates more particularly to means for filling the vertical passage between the chimney and the floor timbers, which are often found when the chimney passes vertically through the floor forming a natural draft through which the air passes when a fire in a house is started.

In most cities it is specified that floor timbers shall not rest against the chimney but must be separated from the chimney by a space which is often 1 inch or more from the chimney.

There is therefore, frequently formed around the chimney a vertical space which may be in width 1 inch or more and which forms a natural upward draft when the house catches fire and adds greatly in the combustion of the material of the house.

My invention has for its object the closing of this natural draft passage by means which are readily put in place and readily fitted to any width of passage.

The invention consists of a sheet of material such as galvanized iron or the like which is folded back and forth to form a stop a little wider than sufficient to fill the space and being readily compressed into said space by compressing the several folds of the sheet against each other.

There is thus formed a stop completely filling the air space and preventing the air from ascending through such a space to fan the flames when such are started.

In addition to a fire stop my device may also be useful for closing up a space which may be utilized by rats and other vermin in finding their way around the house within the partitions.

This space between the floor timbers and the chimney is sometimes filled with cement and sometimes with asbestos but almost all

houses after being built for a while have a tendency to shrink as to the wood-work and when this happens, cracks are often produced in the chimney and between the chimney and the floor. The chimney is also quite liable to settle so that in case cement is used or any rigid construction a crack is liable to be formed.

I have illustrated my invention by means of the accompanying drawing in which:

Fig. 1, is a vertical section through the floor timbers adjacent to the chimney, and

Fig. 2, is a perspective view of my fire stop in position to be placed next to the chimney and forced into the space which it is designed to occupy.

Referring to the drawing 1 represents floor timbers of the house and 2 is a chimney shown in elevation. Between the chimney and the floor timber is inserted my fire stop which consists of a sheet of metal which in one direction is the same width as the chimney and in the opposite direction is folded over in the form of accordion plait, here shown as three in number, so that they will substantially fill the space between the chimney and the floor beam.

A portion 4 and a portion 5 are left straight at the beginning and end of the fold. The portion 5 extending over the top of the floor timbers and the portion 4 folding backward and covering the several folds 6 into which the sheet is divided.

The sheet 3 spoken of is folded up to form a thickness somewhat more than the distance from the floor beam to the face of the chimney.

The corrugations or folds 6 are formed in a series of V-shaped folds so that they can readily be forced down between the floor timber and the chimney with the portion 4 folded over to stop any air passing up through the space.

It will be seen that when my stop is put down between the floor timbers and the chimney, a thing which can be easily done by the foot, it will remain in place stopping the opening regardless of the position of the floor timbers or the chimney sliding verti-

ally along the surface of the chimney when the frame work of the house shrinks.

After the fire stop is in place asbestos or any suitable cement may be inserted between 5 the folds of metal.

I claim:—

A fire stop for the spaces around a chim-

ney and the like, which consists of a sheet 10 of non-inflammable material folded to form a series of horizontal corrugations to fit into said space and having at its top a portion which bends over and covers said corrugations.

BENJAMIN F. FOSS.
